UNITED STATES PATENT OFFICE

149,202

DESIGN FOR A PICTURE FRAME

Syrie Maugham, New York, N. Y.

Application December 13, 1947, Serial No. 143,125

Term of patent 3½ years

(Cl. D29—20)

To all whom it may concern:

Be it known that I, Syrie Maugham, a subject of the Kingdom of Great Britain, residing at 157 West 57th Street, New York, New York, have invented a new, original, and ornamental Design for a Picture Frame, of which the following is a specification, reference being had to the accompanying drawing, forming part thereof.

Fig. 1 is a perspective view of a picture frame, showing my new design.

Fig. 2 is a side view thereof; and

Fig. 3 is a plan view thereof.

I claim:

The ornamental design for a picture frame, as shown.

SYRIE MAUGHAM.
